UNITED STATES PATENT OFFICE.

CHARLES S. FOLSOM, OF SAN DIEGO, CALIFORNIA.

WATER-HEATER REGULATOR.

1,139,408.

Specification of Letters Patent. Patented May 11, 1915.

Application filed November 15, 1911. Serial No. 660,325.

To all whom it may concern:

Be it known that I, CHARLES S. FOLSOM, a citizen of the United States, and a resident of San Diego, in the county of San Diego and State of California, have invented certain new and useful Improvements in Water-Heater Regulators, of which the following is a specification.

My invention relates to devices for regulating the supply of gas to the burners of water heaters which are actuated by the pressure and temperature of the water admitted therein, and the objects are, first, to provide a doubly actuated gas valve that is simple, durable and safe, second, to provide such a valve that is positive in its action, third, to provide such a valve that will not be affected by the overstroke of the thermostat or an over pressure of gas, fourth, to provide a novel means of thermostat and water valve connection to said gas valve, and fifth, to provide a substantial means for rigidly connecting said thermostat, gas and water valves in relation to each other.

With these and other objects in view as will appear, my invention consists of certain novel features of construction, combination and arrangement of parts, as will be herein-after described in detail and particularly set forth in the appended claims, reference being had to the accompanying drawings, and to the characters of reference thereon, which form a part of this specification, in which:—

The figure is a sectional view of my valve shown in operative connection with a water actuated valve and a thermostat, these latter parts being shown in elevation.

Similar characters of reference refer to similar parts throughout the several views.

The casing 1, valve 2, valve 3, spring 4, spring 5, valve stem 6, valve stem 7, stuffing box 8, stuffing box 9, thermostat 10, support 11, and water valve 12 constitute the principal parts of my water heater regulator.

The casing 1 contains two compartments 1^a and 1^b which are connected by a passage 1^c.

In the upper end of the casing in the compartment 1^a is screwed a plug 1^d and in the upper end of the casing into compartment 1^b is screwed plug 1^e. These plugs are adapted to facilitate the placing of the several parts in said compartments.

In the lower surface of compartment 1^a is a valve seat 1^f, and in the lower surface of compartment 1^b is a valve seat 1^g, and adapt-

ed to fit the valve seat 1^f is a packing 2^a which is supported by a flange on the valve 2. Fitting the valve seat 1^g is a packing 3^a which is supported by a flange on the valve 3. These valves are provided with guides 2^b and 3^b adapted to facilitate their engagement with said valve seats.

Connecting with valve 2 is a valve stem 6, which extends out through the plug 1^d and is provided centrally and around said valve stem with a stuffing box 8. Connecting with the valve 3 is a similar valve stem 7 which extends in the opposite direction to valve stem 6, and is provided with a similar stuffing box 9. Connecting with the valve 2 is a compression spring 4, which is adapted to close and to keep the valve closed under certain conditions.

In connection with valve 3 is a compression spring 5 adapted to close and to keep the valve 3 closed under certain conditions.

In line with valve stem 7 and adapted to engage with the end thereof is a water pressure actuated valve stem 12^a, so that when the water pressure in valve 12 causes valve stem 12^a to be pressed outward, it thrusts the valve stem 7 into said valve casing, thereby opening the valve 3 by compressing the spring 5, thus allowing the gas to flow through these compartments in accordance with the flow or amount of water pressure through valve 12.

Connecting with valve stem 6 is a lever 6^a which is pivotally mounted upon a support 11 at the point 11^a, and mounted on lever 6^a is a rod 6^b which connects with a lever 10^a, which is pivotally mounted on support 11 at the point 11^b, and connecting with lever 10^a is a thermostat adjusting bolt 10^b, which is attached to the extended end of the thermostat 10. This thermostat 10 is a single piece of pipe provided with a plug 10^c in its end and having an inlet 10^d and an outlet 10^e. This thermostat is rigidly attached to the support 11, at one end, and is supported by a guide 11^c in which the thermostat is adapted to contract and expand. The thermostat support 11 is shaped as shown in the figure, and is provided with extended lugs 11^d and 11^e, and is provided on one side with a bracket lug 11^f, which is adapted for attaching it to a water heater. This support 11 rigidly connects these valves and the thermostat together, thus providing a positive action.

The operation of the thermostat valve 2

is as follows:—The heated water entering the thermostat through the opening 10^a will heat the thermostat, causing it to elongate, which in turn will relieve the lever 10^a, 5 which will relieve the lever 6^a, thus allowing the valve stem 6 to be pressed into the casing by means of the compression spring 4, which closes the valve 2. If however, the temperature of the water in the thermostat 10 is not too high, the contraction of the thermostat will compress the spring 4, thus opening the valve 2.

It will be readily seen that with this construction, there is provided a good and substantial water heater regulator; that the support connecting the several parts together, provides a means of holding the different parts, rigidly, in their relative positions; that the double actuated valves provide a positive means of regulating the supply of fuel to a water heater; that the single pipe thermostat construction, in connection with the valves, provides a very simple operative means.

Having thus described my invention, what I claim as new and desire to secure by Letters Patent is:—

1. A water heater regulator comprising, a gas valve casing divided into two separate compartments and provided with an inlet and an outlet, a passage way connecting said compartments, a water pressure actuated gas valve, spring seated on the pressure side in one of said compartments, a water pressure actuated valve for opening said gas valve and permitting the flow of gas from one compartment into the other, a thermostat actuated valve normally seated by a compression spring on the pressure side in the other compartment of said casing and adapted to control the flow of gas to a burner, a

thermostat consisting of an elongated hollow casing through which the heated water flows, rigidly mounted on a support at its one end and slidably mounted in a bracket 45 on the same support near its other end and rigidly connected to said casing, and in operative connection with said thermostat operated valve, and said support.

2. A water heater regulator comprising 50 a supporting and connecting frame, provided with a lug near its middle, adapted to be rigidly attached to a water heater, a thermostat consisting of an elongated hollow casing, through which the heated water 55 from the heater flows, rigidly secured to said frame at one of its ends near the end of said frame, a guide rigidly secured to said supporting frame near the middle in which the other end of said thermostat is 60 shiftably mounted, a doubly actuated fuel supply valve rigidly secured to said supporting and connecting frame, operative connections mounted on said frame between said supply valve and said thermostat whereby the 65 movement of said thermostat is enlarged to one of the actuating portions of said supply valve, and a water pressure actuated valve for actuating the other portion of said gas valve rigidly secured to said supporting 70 frame, whereby said thermostat, fuel supply valve, operative connections and water pressure actuated valve are rigidly secured and connected together.

In testimony whereof, I have hereunto 75 subscribed my name in the presence of two subscribing witnesses.

CHARLES S. FOLSOM.
